D. C. DOZIER

VEHICLE HEADLIGHT

Filed Nov. 5, 1923

Attorney

UNITED STATES PATENT OFFICE.

DANIEL C. DOZIER, OF NORFOLK, VIRGINIA.

VEHICLE HEADLIGHT.

Application filed November 5, 1923. Serial No. 672,899.

To all whom it may concern:

Be it known that I, DANIEL C. DOZIER, a citizen of the United States, residing at Norfolk, in the county of Norfolk and State of Virginia, have invented certain new and useful Improvements in Vehicle Headlights, of which the following is a specification.

My invention relates to vehicle headlights.

The object of the invention is to provide an efficient headlight for automobiles which contains advantageous features which will be more fully described herein and specifically pointed out in the claims hereunto annexed recourse being had to the accompanying drawing forming a part of this specification in which:—

Figure 1 is a sectional view of one form of my device taken on the line 1 in Figure 2.

Figure 2 is a front view.

Figure 3 is a rear view.

Figure 4 is a front view detached from the incandescent lamp.

Figure 5 is a plan of my device removed from the lamp.

Figure 6 is a plan of the colored light transmitting arc shaped plate.

Figures 7, 8 and 9 are elevations of modified forms of shades.

Figure 10 is a sectional view of a modified form of half shade or lamp cover.

Figure 11 is a sectional view of a reflector of a headlight showing the manner of distributing the rays of light from my device.

Figure 12 is a front view of the same.

In the drawing like reference numerals indicate similar parts in all the several views:—

1 represents an elevation of an incandescent lamp used for headlights of automobiles and is provided with a base 2 fitting into the socket 3, in the ordinary manner.

4 is a shell or half shade having a straight or horizontal front portion and a rounded rear portion, as shown in Figure 1, while in Figure 10, I show a modified form 5 wherein the whole shade is semi-elliptical and which will be described hereafter.

6 is an orifice which partly surrounds the lamp base 2.

7 is a circular shaped spring soldered, or otherwise fastened to the inner rear portion

of the shade 4 or 5 and is adapted to have a spring fit over the base 2 to hold the shade 55 in place upon the lamp.

To further support the shade and allow for the insertion of any size lamp, I provide a spring or springs 8 extending across the diameter of the shade, from side to side, 60 as at 9, and located under the lamp 1 as shown in Figures 1, 2 and 10 thereby holding it in a yieldable manner and capable of being distended according to the size of the lamp which is inserted over the spring 65 until the spring 7 engages the lamp base 2.

10 is a slot placed in the top of the shade 4 or 5 and extends, with decreasing width, about two-thirds of its circumference and is shaped like a segment of a circle formed 70 by a chord and the arc of a circle.

Over the opening 10 I place a curved glass or mica plate 11 of one or two colors, for example, one red portion 12 and a green portion 13, Figure 6, for emitting a crescent 75 shaped glow on the head light reflector and lens, as shown in Figures 11 and 12, also for causing different colored rays to be cast upwards or at an angle as will be described hereafter.

The glass plate 11 may be of even width throughout or have reduced ends 11^a, if desired, shown in Figure 6. The plate 11 is inserted under the spring tongues 14 and pushed towards the rear of the shell 85 or shade 4 or 5 until its outer edge slips below the projection 15 which holds it in place. If the glass 11 is divided into two colors or perhaps three colors, it may be moved so that any color may be used, if 90 desired.

16 is a narrow strip formed with the shade 4 and terminates with the disc or plate 17 and is for the purpose of shading the direct rays from the source of light, as in Figure 95 2, while in Figure 10 I make the shade so that its outer edge will extend a little below the horizontal centre line 18 of the lamp 1.

19 is a depression which forms a knob on the inside of the shade 5, Figure 10, and is for the purpose of resting upon the upper part of the lamp and assists in keeping it in place and allowing for an air circulating space for keeping the shell or shade cool.

In Figure 1, 20 represents, by dotted or broken lines, the location of a possible side

opening in the shell 4 or 5, and 21 are similar lines showing an apron for further shading the light if it is desired to use such.

In Figure 9 I show an inclined light deflecting shade having an angle 22 of approximately 7 $\frac{1}{2}$ degrees. I also show the top of the shade perforated at 23 arranged to form a shape like that at 10 and occupying approximately the same area.

10 In Figures 11 and 12 I show my invention within the reflector of a headlight, as at 24, showing the reflection of the rays in the ordinary manner, the arrows 26 indicating the upward or angular rays through the glass 11 passing through a suitable orifice in the top of the reflector, as at 25, though my device may be used without the reflector 24, if desired.

15 The colored rays through the glass 11 are thrown at an angle ahead of the automobile and if the tail lamp should go out, a following car driver may see them and would identify fire apparatus if so equipped as well as ordinary automobiles. The shape of the slot

20 25 10 covers a part of the reflector 24 with a crescent shaped light area, as at 25 in Figure 12, and if suitable marks or letters are placed on the plate 11, they would be visible in a magnified manner upon the reflector.

25 30 In this manner, one car may be distinguished from another by proper identifying marks.

35 My device may be arranged so that the light may be thrown to the right or left acting also as a light diffuser and the colored rays are so distributed that they will be raised so as to be distinguished above the bright lights of oncoming cars and prevent blinding.

40 My invention can be used in headlights having ordinary cheap glass and my invention may be readily replaced and be free from injury. It also provides a substitute for expensive glass lenses, will eliminate

glare, and may be placed in the headlight without taking the lamp from its socket. 45

I claim:

1. In combination with an electric incandescent lamp, of a shade adapted to be spring fitted around the bulb of the lamp, a segmental opening therein, a multi-colored light emitting medium thereover, and spring means for holding the multi-colored medium over said opening. 50

2. In combination with an electric lamp, a half shade or shell therefor, double spring means for holding the same to the lamp, an opening on the shade and over said lamp adapted to direct the rays upwards and at an angle, light transmitting means over said opening, means on said half shade for keeping the lamp from direct contact therewith, and a disc formed from the shade adapted to cover the end of the lamp for throwing the rays below a horizontal line from the centre of the lamp. 55

3. In combination with an electric lamp and its reflector, of a shade adapted to be secured to two portions thereof, spring means for both of said parts, an opening in said shade, and a colored light emitting medium for casting a glow upon said reflector of approximately a crescent shape. 60

4. A headlight and in combination with its lamp and reflector, of a shade for the lamp having means for directing white rays downwards and sideways, an opening in the shade, a double colored glass cover for said opening adapted to emit colored rays upwards, at an angle and upon a part of said reflector, and spring holding means for the shade positioned at the end and under said lamp. 75

In testimony whereof I have hereunto affixed my signature.

DANIEL C. DOZIER.
